METHOD OF MAKING U-SHAPED PIPE-BENDS.

1,133,017.

Specification of Letters Patent. Patented Mar. 23, 1915.

Original application filed April 5, 1912, Serial No. 683,649. Divided and this application filed January 12, 1914. Serial No. 811,558.

To all whom it may concern:

Be it known that I, NIELS CHRISTOPHER FRANDSEN, a subject of the King of Denmark, residing at Copenhagen, in the Kingdom of Denmark, have invented a new and useful Improvement in Methods of Making U-Shaped Pipe-Bends, of which the following is a specification.

My invention relates to a method by means of which two pipe ends may be so shaped that they can at once be welded together to constitute a single pipe united by a U-shaped pipe bend. My invention has especial utility in the manufacture of superheater pipes for smoke tube superheaters, such pipes generally having two or more adjacent legs united by U-shaped bends.

My invention will be better understood by referring to the drawings accompanying in which—

Figure 1 represents an end elevation of a preferred form of a die, by means of which the method may be practised; Fig. 2 represents a section taken along the line 2—2 of Fig. 1, a pipe end being shown *in situ*; Fig. 3 represents, on a smaller scale the die opened as is required for the removal of a formed pipe end; Fig. 4 represents in central longitudinal section a pipe end ready to be formed; Fig. 5 represents in section two formed pipe ends as they appear when positioned for welding or after being welded, the section being taken in the plane of the pipes; and Fig. 6 represents in section, a complete pipe bend having its points reinforced.

Essentially, the die embodies a body portion comprising two, preferably substantially similar, hinged sections each of which is scooped out in the form which half of a pipe end is to have after it is bent. The two sections of the die being closed together, provision is made for an inner horn or mandrel attached to the die to be swung into that portion of the die which represents the bend of the completed pipe end in such a way as to constitute a core spaced away from the die walls (*i. e.* the walls of the scooped out portions) so that the pipe end when suitably heated and forced into the

die will be bent into the required curve between the horn and said die-walls.

My invention will be better understood by referring to the drawing in which—

A designates the lower section of the die and B the upper section which is hinged to the lower section by a pintle C at the left of the die. At the right, each section of the die is scooped out so as to conform to the shape which a half pipe end should have after said pipe end has been bent ready for welding to the other pipe end. When the two halves of the die are closed together, therefore, these two scooped-out portions exactly conform in configuration to the shape of a finished pipe end.

A separate piece H extending beyond the top and bottom of the combined and closed die sections, is provided with tongues F which closely embrace the die when the two halves are thus closed together. These tongues are suitably cut away so as to engage journals E fixed to the two halves of the die. The piece H has attached to it, midway between the tongues F, a curved horn or mandrel D so positioned that when the piece H with its tongues F is rotated upon the aforesaid journals E, this horn will register with the curved portion of the die in the region corresponding to the tube end so as to be substantially concentric with but spaced from the curved walls of the die. When the horn is thus positioned, a flat bolt M is slipped through suitably located bolt holes G which have been formed both in the tongues F and in the two die halves A and B so that said two halves and the horn D are rigidly locked together.

My method is practised as follows: A pipe end of diameter corresponding to the scooped out portion of the die is sawed off at an angle L (Fig. 4). This pipe end is then heated to a red heat and forced into the straight portion of the die opening N' (Fig. 2), so that the point L of the tube end will strike the curved portion of the die at I; this will cause the pipe end, if sufficient pressure be applied, to be bent around the curved portion of the die opening between the wall thereof and the horn D. If it is

desired that the pipe end shall be thickened or reinforced at and near its point at the outer side thereof, this may be readily accomplished by having the scooped out portion of the die in this region enlarged to any desired extent, as shown for example by the dotted line N, Fig. 2. By suitably defining this region of enlargement, the wall thickness of the finished pipe end may be made 5 to lessen gradually from a maximum at the point of the pipe end to a normal thickness at any chosen distance from said point end. Fig. 6 shows a finished pipe bend thus reinforced. This reinforcing is very desirable 10 in superheater pipes in order that they may withstand the heat of the furnace gases which is most intense at the points of the U bends lying adjacent to the fire box. A single pipe end having been formed as above described, the bolt M is knocked out and the piece H with its tongues F rotated upon the journals E so as to withdraw the horn D from the die opening. A suitable number 15 of pipe ends having been formed, they may then be joined together in pairs as indicated in Fig. 5, and the ends welded in any convenient manner.

I have described my invention as practised with a die for forming one pipe end at a time, but dies providing for bending a number of pipe ends simultaneously may easily be arranged.

As described the die is operated by hand but it may, if preferred, be operated by 30 power within the scope of my invention.

This application is a division of my prior application entitled "Die for making U-shaped pipe bends", Serial Number 688,649, filed April 5, 1912.

Having described my invention, I claim: 40
1. The improvement in the art of making U-shaped pipe bends which comprises taking a piece of straight pipe, applying axial and lateral pressure to opposite end walls 45 thereof so as to both compress and bend the end of the pipe and simultaneously maintaining an outward pressure upon the inside of the end wall of the pipe.

2. The improvement in the art of making 50 U-shaped pipe bends which comprises taking a piece of straight pipe, heating the end thereof, applying axial and lateral pressure

to opposite end walls thereof so as to both compress and bend the end of the pipe and simultaneously maintaining an outward pressure upon the inside of the end wall of the pipe.

3. The improvement in the art of making U-shaped pipe bends which comprises taking a piece of straight pipe, cutting off said pipe so as to have an elliptical section, applying axial pressure to the wall about the circumference of the ellipse and lateral pressure to the pipe end in that plane of the pipe which includes the major axis of the ellipse so as to both compress and bend the end of the pipe and simultaneously maintaining an outward pressure upon the inside of the end wall of the pipe.

4. The improvement in the art of making U-shaped pipe bends which comprises taking a piece of straight pipe, cutting off said pipe so as to have an elliptical section, heating the end thereof, applying axial pressure to the wall about the circumference of the ellipse and lateral pressure to the pipe end in that plane of the pipe which includes the major axis of the ellipse so as to both compress and bend the end of the pipe and simultaneously maintaining an outward pressure upon the inside of the end wall of the pipe.

5. The improvement in the art of making U-shaped pipe bends which comprises taking a piece of straight pipe, cutting off said pipe so as to have an elliptical section, applying axial pressure to the wall about the circumference of the ellipse and lateral pressure to the pipe end in that plane of the pipe which includes the major axis of the ellipse and in a direction which will bend the pointed end of the pipe toward the axis of said pipe so as to both compress and bend the end of the pipe and simultaneously maintaining an outward pressure upon the inside of the end wall of the pipe.

In testimony whereof I have hereunto set my hand in the presence of two subscribing witnesses.

NIELS CHRISTOPHER FRANDSEN. [L.S.]
